FLUSH MOUNTED LAMP FIXTURE
 Georges Houplain, 33 Rue des Fontaines,
 Sucy-en-Brie, Seine-et-Oise, France
 Filed Dec. 1, 1958, Ser. No. 777,458
 2 Claims. (Cl. 248—343)

The present invention relates to a lamp holder, orientable or otherwise, embedded in the ceiling, used for obtaining lighting in which the light sources are concealed as much as possible.

It has more particularly the object of producing a holder comprising solid securing lugs affording an efficient hold in the ceiling and able to stand up to repeated dismounting.

Another object of the invention is to produce said securing lugs that can be removed from the lamp holder so as to reduce the space required or for storage and avoid risks of breakage during transportation.

The invention applies more particularly to the characteristics hereinafter described and to their various possible combinations.

An orientable lamp holder, for embedding, is shown by way of non-restrictive example in the attached drawings, in which:

FIGURE 1 shows a cut away view of the lamp support mounted in a ceiling;

FIGURE 2 shows a top plan view of the holding disk;

FIGURE 3 is a longitudinal sectional view of the securing lug;

FIGURE 4 shows a cross-sectional view of said lug;

FIGURE 5 shows a fragmentary sectional view of the clip;

FIGURE 6 shows a top plan view of said clip;

FIGURE 7 shows a longitudinal sectional view of the mounting of the lug on the clip;

FIGURE 8 shows a fragmentary top plan view of the mounting with the lug in cross-section.

The holder to be embedded shown in FIGURES 1 and 2 comprises more particularly:

A semi-spherical body 1 surmounted by a hoop holding the socket 2 into which the cap of the lamp 6 is screwed and resting on a truncated supporting base 3.

At its truncated part 3₁, said base 3 swivelably holds the semi-spherical body 1, thus enabling its orientation, and at its flat part 3₂ has a flange 3₃ for accommodating the clip 8 in which the securing lug 7 is mounted.

This arrangement enables the flange 3₃ to be perfectly applied to the ceiling 9 and to hold the base 3 by bending the securing lug 7 on the other side of the ceiling.

It is clearly understood that it is necessary to provide the base 3 with several clips 8 and lugs 7 in order that a perfect attachment takes place under the ceiling.

For a better understanding of the device, we herein-after describe, by way of non-restrictive example, a lug 7 and its clip 8.

The lug 7 shown in FIGURES 3 and 4 comprises more particularly:

A vertical body 7₁ stiffened by two flanges 7₂ and 7₃ more pronounced at the top part 7₄ than towards the bottom 7₅.

The top part of the body 7₄ will act as a pivot axis at the moment when it is required to bend the lug on to the ceiling. At this moment, the teeth 7₅, 7₆, 7₇, 7₈, provided on each of the flanges 7₂ and 7₃ will bite into the ceiling 65 for effecting a secure hold.

2

At its bottom part, the lug comprises a base 7₉ perpendicular to the body 7₁ drilled in the shape of a slot 7₁₀.

The clip shown in FIGURES 5 and 6 comprises more particularly a tongue 8₁ perpendicular to the flange 8₂ fixed on two bases 8₃ and 8₄.

Between the two bases there is a T-shaped notch, whose two internal shoulders 8₅ and 8₆ are formed to receive the lug portion 7₉.

The mounting of the lug 7 in its clip 8 is clearly shown 10 in FIGURES 7 and 8, in which can more particularly be seen:

The supporting base 3 includes the flat part 3₂ and the flange 3₃ to which the clip 8 is permanently attached by its bases 8₃ and 8₄ by soldering, riveting or the like.

15 The removable lug 7 is fixed in the clip 8 by means of its base 7₉ which is embedded between the two bases 8₃ and 8₄ and under the shoulders 8₅ and 8₆ of said clip 8.

To perfect rigidity, the tongue 8₁ of the clip engages in the slot 7₁₀ of the lug.

20 A thrust in the direction of the arrow F₁ (FIGURE 7) will bend the lug 7 above the ceiling 9 ensuring a rigid hold by inserting the teeth into said ceiling.

On the other hand, the base assembly 3 not being embedded in the ceiling, a crosswise movement of the lug 7 25 in the direction of the arrow F₂ will enable it to be easily removed by disengaging the base 7₉ and the slot 7₁₀ from the raised shoulders 8₅ and 8₆ and the tongue 8₁.

It is quite obvious that the invention is not restricted to the example of embodiment described and shown and 30 from which several alternatives can be obtained.

In particular, the example of utilization has been taken with an orientable lamp holder for embedding, but it is quite obvious that it could be used with a non-orientable holder.

35 What I claim is:

1. In a flush mounting adapted to fit in the ceiling recess for a lamp including a supporting base, the improvement comprising an anchoring bracket having two legs of unequal length disposed at an angle to one another; the longer leg being stiffened by flanged edges, tapering and increasing in width from the vertex of said angle to the end of said longer leg to increase the resistance to bending near said end of said longer leg, said flanged edges having teeth formed thereon in the plane therewith, said longer leg being adapted to be bent around and above the edges of said recess in such a way that said teeth will bite into the edge of said recess and the upper surface of said ceiling; and the shorter leg being secured to the said supporting base by means of a tongue on said base passing through a slot in said longer leg adjacent said vertex of said angle.

2. Apparatus in accordance with claim 1 wherein said tongue comprises a projection from said base having two legs of approximately equal length at right angles to one another, one of said legs being perpendicular to the part of said supporting base from which it projects and the other leg, engaging said slot in said longer bracket leg, being parallel to said part of said supporting base.
